Specification for Design.

Patented Oct. 4, 1921.

Application filed November 19, 1920. Serial No. 425,278. Term of patent 14 years.

To all whom it may concern:

Be it known that I, JAMES J. COLLINS, a citizen of the United States of America, residing at Springfield, in the county of Hampden and State of Massachusetts, have invented a new, original, and ornamental Design for Tags, of which the following is a specification, reference being had to the accompanying drawings, forming part thereof.

In the drawings, Figure 1 is a plan view of a tag showing my new design; and, Fig. 2, an edge view of said tag.

I claim:

The ornamental design for a tag, as shown.

JAMES J. COLLINS.
